CLAIM

The ornamental design for a shelf for an automobile spray paint booth or the like, as shown and described.

DESCRIPTION

FIG. 1 is a top, front, and right side perspective view of a shelf for an automobile spray paint booth or the like showing my new design;

FIG. 2 is a top, front, and right side perspective view thereof, with the shelf shown in its folded position;

FIG. 3 is a bottom plan view thereof;

FIG. 4 is a right side elevational view thereof; the left side being a mirror image of that shown, and

FIG. 5 is a front elevational view thereof.

The broken-line depiction of a portion of a wall surface in the views is for illustrative purposes only and forms no part of the claimed design.
